UNITED STATES PATENT OFFICE

2,577,356

CIGARETTE HUMIDIFIER

Gustandy Otallah, Detroit, Mich.

Application October 21, 1950, Serial No. 191,453

5 Claims. (Cl. 312—31)

1

This invention relates to improvements in cigarette humidifiers, and is of the same general order as the humidifier shown in my co-pending application Serial No. 769,007, now Patent No. 2,534,829. One of the main purposes of that invention was to provide a humidifier having means therein for preventing tobacco from the cigarettes falling into the water used for keeping them moist, since water in which pieces of tobacco have dropped gives off a most unpleasant odor. In the case above referred to tobacco was prevented from falling into the water by a conical perforated cover provided over the water pan so that tobacco dropping onto the latter passed downwardly and outwardly thereover. The objection, however, to that arrangement lay not in the construction employed, but in the fact that people too often forgot to replace the cover after renewing the water supply. Then, obviously, there was nothing to prevent any falling tobacco from dropping into the water pan.

It is an object of this invention to provide a cigarette humidifier so constructed as to prevent, to a very large extent, tobacco falling into a water pan therein, and wherein this is accomplished without resorting to the use of a removable cover, which is so liable to become lost or misplaced, over the pan.

Another object of the invention is to provide a cigarette humidifier wherein the water pan is integral with the base and so supported relative to the latter that if the device is bumped water from the latter is neither spilled on the table on which the device rests, nor do the cigarettes become wet, unless the bump is very severe indeed.

A further object of the invention is to provide a cigarette humidifier which is both cheap and simple to manufacture, and efficient in operation.

Having thus stated some of the objects and advantages of the invention I will now describe it in detail with the aid of the accompanying drawing in which

Figure 1 is a plan view of the invention, and

Figure 2 is a section on the line 2—2 of Figure 1, and also shows a transparent cover mounted upon the device.

Referring to the drawing, 1 designates a base having a water pan 2 supported concentrically therein. In the present instance the pan 2 is held by an annular plate 3 which is integral both with the said pan and with the base. The plate 3 which is downwardly and inwardly inclined from the base to the pan extends from adjacent the top of the base 1 and joins the pan 2 inter-

mediately of the height of the latter so that if on account of sudden movement of the device some water is spilled from the pan it is caught upon the plate and neither runs off the latter nor wets cigarettes supported thereover unless the humidifier is very severely jolted or tipped at an excessive angle.

Projecting upwardly from the base 1 around the outer periphery of the plate 3 is an annular flange 4 in which the lower extremity of a support member 5 is mounted. Formed integral with and projecting upwardly from the member 5 are a plurality of substantially concentric rows of cigarette holders 6; in the present instance each row is arranged at a different elevation with the innermost row highest and the outside row lowest. Each holder 6 is tubular to receive and support a cigarette A and is vertically split from its upper extremity as shown at 7 for a portion of its height rendering it resilient and thereby facilitating either the insertion or removal of a cigarette. Moreover to further simplify this operation the upper extremities of the opposite split sides of the holders 6 are chamfered as shown at 8. Former integral with the support member 5 are a plurality of cone-like baffles 9 one of which is formed in the lower extremity of each tubular holder 6, and projecting centrally and vertically through each of the said portions 9 is an opening 10 for the upward passage of moisture-laden air therethrough. It will thus be noted that due to the conical formation of the upper faces of the baffles 9 that any tobacco that drops onto the latter is caught between the baffles and the bore of the holders, and is thus prevented from falling into the water pan 2 and thus causing a most objectionable smell. It is only very rarely that tobacco drops into one of the openings 10, which for the sake of clarity are shown larger than they really are, and even when that happens it usually remains therein and does not fall into the water pan.

A cover 11, preferably transparent, may be mounted for removal upon the member 1, as shown in Figure 2, to protect the cigarettes from dust and dirt, and also to retain the moisture rising from the water pan in propinquity to the cigarettes.

While in the foregoing the preferred embodiment of the invention has been described and shown, it is understood that alterations and modifications may be made thereto provided the said alterations and modifications fall within the scope of the appended claims.

What I claim is:

1. A humidifier including a base, a water pan supported therein, a support member mounted on the base and spaced above the water pan, a plurality of vertical, tubular cigarette holders integral with the supporting member, a centrally and vertically apertured cone in the lower extremity of each tubular holder, the lower peripheral portion of each cone merging with the bore of its holder to form an annular recess to catch tobacco falling from a cigarette supported in that holder, thereby to prevent the falling tobacco from dropping through the lower extremity of the holder into the water pan.

2. A humidifier including a base, a water pan, an annular plate extending downwardly and inwardly from the base to the pan, said plate being integral with both said base and said pan, said plate being imperforate to catch and retain water spilled from the water pan, a support member on the base spaced over the water pan, a plurality of tubular cigarette holders vertically arranged in the member, and means in the lower extremity of each tubular holder for catching tobacco dropping from a cigarette resting therein to prevent it dropping into the water pan, said means being vertically apertured for the passage of moist air from the water pan to the cigarettes.

3. A humidifier including a base, a water pan, an annular plate extending downwardly and inwardly from the base to the periphery of the water pan, said plate being integral with both said base and said pan, said plate being imperforate to retain water spilled from the pan, a support member mounted on the base and spaced above the water pan, a plurality of tubular cigarette holders carried vertically by the supporting member, each holder having an axially apertured cone in its underside, the lower peripheral portion of each cone merging with the bore of its tubular holder to form an annular recess to catch tobacco dropping from a cigarette mounted in that holder thereby to pre-

vent tobacco falling from the holder into the water pan.

4. A humidifier including a base, a water pan, an annular plate extending downwardly and inwardly from the base to the pan, said plate being integral with both said base and said pan, said plate being imperforate to retain water spilled from the pan, a support member on the base spaced over the water pan, a plurality of tubular cigarette holders integral with and projecting upwardly from the member, the upwardly projecting extremities of the holders being vertically split to render them resilient to facilitate their engagement or disengagement with a cigarette, and vertically apertured means in the lower extremities of the holders for preventing tobacco dropping from cigarettes in said holders into the water pan.

5. A humidifier including a base, a water pan 20 therein, a support member on the base over the water pan, a plurality of tubular cigarette holders integral with and projecting through and above said member, the upper extremities of the holders being split to render them resilient to 25 facilitate their engagement or disengagement with a cigarette, and axially apertured cones in the lower extremities of the holders and integral with the member, said cones being spaced above the pan, the lower peripheral portions of the 30 cones merging with the bores of the tubular holders to form annular recesses to catch tobacco dropping from cigarettes mounted in the holders, thereby preventing tobacco falling from the cigarettes into the water pan.
